A. E. BARNARD, OF AKRON, OHIO.

Letters Patent No. 86,629, dated February 9, 1869.

IMPROVED DIE FOR BENDING EQUALIZING-BARS.

The Schedule referred to in these Letters Patent and making part of the same.

To all whom it may concern:

Be it known that I, A. E. BARNARD, of Akron, in the county of Summit, and State of Ohio, have invented certain new and useful Improvements in Devices for Bending Equalizing-Bars; and I do hereby declare that the following is a full and complete description of the same, reference being had to the accompanying drawings, making part of this specification, in which—

Figure 1 is a side view of the apparatus.

Figures 2 and 3, detached sections.

Like letters of reference refer to like parts in the several views.

The nature of this invention relates to a forming-block, or die, wherein are forged or shaped equalizing-bars, so that any number of bars may have one equal length and an exact curvature.

In fig. 1, A represents a block or lower die, in which is cut a groove, B, fig. 3, the depth of said groove being equal to the difference of the width and thickness of the bar.

C is a steadyng-bar, proceeding outward from the block, and in which it is secured, so that the upper edge of the same shall be even with the bottom of the groove.

It will be observed that the upper side of the block or die is curved, so also the groove cut therein, said curve being that required to be given to each end of the equalizing-bar, as shown at D, fig. 1.

E, fig. 1, is an upper die, or hammer, the face of which is curved so as to correspond with that of the die A. The face of the upper die is plain and smooth, there being no groove cut therein, as shown in the lower one.

Equalizing-bars are usually made by hammering them into shape, giving the proper curve by bending the bar over some rounded corner. This manner of forging them is one of great labor, and very uncertain in its results, as the bars are not all bent of the same curve without great care being exercised in the operation.

To avoid this trouble, labor, and expense, is the purpose of the above-described apparatus, the practical operation of which is as follows:

A bar of iron, of the proper length and thickness for an equalizing-bar, is prepared, one end of which

being heated, the bar is then secured to the steadyng-arm C, by means of the strap G, which is made fast thereto by means of the key and gib H, the heated end resting in the groove B in the thick part of the block. It is then bent by the forming-hammer E, operated by a tilt in the ordinary way, which, by a succession of blows, bends the end down into that section of the groove cut in the reduced end of the block, thereby giving to the bar the exact curve required.

That portion of the width of the bar above the groove being equal to the thickness of the bar, brings the face of the hammer parallel to the face of the block or die A when the bar is bent; hence the blows of the hammer will be given to the entire face thereof. Therefore, when the bar is laid flat upon the die, for straightening and smoothing off after being bent, it will receive the blows of the hammer horizontally, or parallel with the face of the die; hence, the bar will be of a uniform thickness, which would not be the case if the blows were given at an angle to the face of the block.

It will be observed that the width of the groove is greater at the rear end than at the front, to allow the metal to expand, and thereby increase its thickness and strength.

One end of the bar having been formed, the opposite end is now heated in the same way by placing the bar again upon the arm C, so as to bring the curve at D, in exact relation to that given to the end of the arm, which answers as a gauge, whereby the length of the bar is determined.

By this means any number of equalizing-bars can be forged, all of the same length, and of a uniform curvature, which cannot be done in the ordinary way without the use of much time and skill, which renders the bars much more expensive than when forged in the dies, as above described.

What I claim as my improvement, and desire to secure by Letters Patent, is—

The die or block A, groove B, and steadyng-bar, or arm, C, in combination with the hammer E, for the purpose specified.

A. E. BARNARD.
